ATTORNEY.

UNITED STATES PATENT OFFICE

CHARLES HOPKINS, OF POTTSTOWN, PENNSYLVANIA

DIE

Application filed November 20, 1929. Serial No. 408,490.

This invention relates to dies and has for its general object the production of a die for the stamping out of articles of manufacture having recesses or shoulders, slots and bores or holes.

This invention relates particularly to dies for use in punching hot press nuts which in addition to the usual bore for the thread have a circumferential recess or shoulder such as shown at 30 in Figure 14 and one or more slots, such as 32 in Figure 14, leading from the outer surfaces of said nuts to the said shoulder or circumferential recess 30.

I achieve my object by using in combination a punch, a die carrying slotting elements, a piercer having a recess forming element thereon and a crowner having slots therein.

The dies herein disclosed are adapted for use in the well known hot press nut punching machines now on the market and for that reason only the dies will be here described.

More particularly stated one of the objects of this invention is to produce a die for the stamping out of articles of manufacture having recesses or shoulders, slots leading into said recesses and bores or holes.

Another object of this invention is to produce a die for use in punching hot press nuts which in addition to the usual bore for the thread have a circumferential recess or shoulder and one or more slots leading into said shoulder from the outer surface of said nuts.

Another object of this invention is to produce dies for the particular purpose set forth which shall be simple in construction, easy to assemble and comparatively cheap to produce.

These and other objects and advantages of this invention will be clearly seen from the following description and the drawings which form a part hereof.

In the drawings Figure 1 is a view in section of the die elements assembled, the machine parts to which the individual elements are attached being omitted. As shown one of the positions assumed by the component dies in the process of manufacture of a nut is shown in full lines and another position is shown in dotted lines.

Figure 2 is a front view of the dies carrying the slotting elements and a completed nut lodged in said die part of said view being shown in section along the line 2—2 of Figure 3.

Figure 3 is a top view of the assembly of dies carrying the slotting elements and a completed nut lodged in said dies.

Figure 4 is an enlarged sectional view on the line 4—4 of Figure 3.

Figure 5 is a front view of the crowner.

Figure 6 is a fragmentary top view of the crowner showing the slotted end.

Figure 7 is a section taken along the line 7—7 of Figure 5 showing the fragment of the crowner shown in Figure 6.

Figure 8 is a front view of the punch.

Figure 9 is a perspective showing a punch for square nuts.

Figure 10 is a front view of a piercer showing a shoulder adapted for punching a tapered circumferential recess such as shown at 36 in Figure 18.

Figure 11 is a fragmentary side view of the piercer shown in Figure 10.

Figure 12 is a perspective view of a two slot hexagon nut, a product of the dies herein disclosed.

Figure 13 is a perspective view of a three slot hexagon nut having a tapered circumferential groove a product of the dies herein disclosed.

Figure 14 is a perspective view of a two slot square nut a product of the dies herein disclosed.

Referring more particularly to the drawings wherein similar reference designate similar parts, reference numeral 1 denotes the assembly of the slotting element carrying dies 2, the punch 3, the piercer 4 and crowner 5 in operative position and in the process of punching out a two slot hexagon nut 29.

The punch 3 is shown in one position by the solid lines designed by letters A B C D and in another position by the dotted lines 95 designed by letters A' B' C' D'. The piercer 4 is shown in one position by the solid lines designed by letters J K L M and in another position by the dotted lines 100 designed by letters J' K' L' M'. The crowner 5

is shown in one position by the solid lines designated by letters E F G H and in another position by the dotted lines designated by letters E' F' G' H'.

5 The slotting element carrying dies are composed of an upper member 6 and a lower member 7. The members 6 and 7 have holes 8 and 9 formed therein of such shape that together they bound and form a hexagon 10 shaped aperture. The upper and lower elements each have a slot 10 formed therein in which is carried the slotting element 11.

Each slotting element 11 is composed of a main body portion 12, a cutter proper 13 15 which extends into the aperture 8-9 and an ear 14 at right angles to said main body portion 12. An aperture 15 is formed in said ear 14 through which a screw 16 is adapted to pass and fasten the slotting element 11 to its 20 respective die member 6 or 7.

The punch 3 is composed of a main body member, one end of which is free and punches out the nut while the other end is firmly held by a machine element here not shown. The 25 punching face 17 of the punch 3 is hexagon shaped adapting same to punch hexagon nuts. A hole 18 is bored through the entire length of the punch 3 whereby metal which is punched out by the piercer can be eliminated 30 from the machine.

The piercer 4 is made of a cylindrical main body portion 21, threaded at one end 22 for insertion into and engagement by the machine element (not shown) which is to carry and 35 actuate the same. The free end terminates in a cylindrical boring element 19 of smaller diameter than the main body portion 21. A shoulder 20 is formed at the point of junction of the elements 19 and 21.

40 The crowner 5 is a hollow cylinder having an aperture 25 adapting it for mounting and movement on the main body member 21 of the piercer 4. The crowner 5 consists of a main body member 23 threaded at one end 24 for insertion into and engagement by the machine element (not shown) which is to carry and actuate the same. The face of the free end of the main body member 23 terminates in a crowning surface 28 properly shaped to impress the crown surface on the nuts. The main body member 23 is hexagon shaped in cross-section having a plurality of bounding surfaces 27. Slots 26 are formed in the members 27 at points where they will 50 register with and receive the cutter 12. The slots are of sufficient length to permit the necessary movement of the crowner.

Although the method of operation and uses of the elements here outlined are believed to be obvious, nevertheless for the purpose of obviating any possibility of misunderstanding the following detailed description is here given.

55 The slotting element dies 6 and 7 are inserted in the nut punching machine. The punch-

er 3, the piercer 4 and crowner 5 are also mounted in place, the relative position of all of these elements with respect to the dies 6 and 7 and each other being shown by the dotted lines in Figure 1. Metal is now fed 70 in on the punch side of the dies 6 and 7. The punch 7 is moved forward by the machine element which carries it, punches a hexagonal piece of metal into the opening 8-9 of the dies 6 and 7 and finally assumes the position 75 A B C D shown by the solid lines in Figure 1.

As the metal is forced into the opening 8-9 it comes into contact with the cutters 11 which punch the slots 32 in the metal. In the next operation the piercer is moved forward 80 by machine element which carries it finally assuming the position shown by the solid lines J K L M. The portion 19 of the piercer punches the hole 31 in the nut. The piercer enters the nut a sufficient distance to permit the shoulder 20 to form the circumferential groove 30 of proper depth. The metal punched out by the piercer 4 enters the aperture 18 in the punch 3, each succeeding piece of metal pushing forward that 85 which preceded it, the punched pieces being finally discharged from the far end of the punch 3. In the next operation the crowner is moved forward by the machine element which carries it and finally assumes 90 the position shown by the solid lines E F G H. In this position the slots 26 receive the free ends of the cutters 12 and the crowning surface 28 crowns the surface of the nut. In the next operation the punch is moved back 95 by the machine element which carries it to its original position shown by the dotted lines A' B' C' D'. At the same time the crowner 5 is moved forward a distance sufficient to push the nut out of the aperture whence it 100 falls into a container. The slots 26 permit the movement of the crowner 5 with respect to the cutters 12. The crowner now moves backward, metal is fed to the machine, the punch moves forward and another cycle begun.

105 The above disclosure is by the way of illustration only and not by the way of limitation since many changes may be made in the above disclosure without departing from the spirit of my invention. For instance any type of nut may be punched such as a square nut 33 shown in Figure 14 or any other geometric shape desired. To do that the geometric shape of the apertures 8 and 9, the crowner 5 and the punch 3, is changed to conform with the geometric shape desired for the nut. Figure 9 shows a punch 37 having a square face 38 and bore 39 adapted for punching square nuts. Instead of making a nut with two slots one, three or any number of slots desired may be made. This is done by merely removing or inserting the number of cutters necessary and cutting the necessary cooperating slots in the crowner. A hexagon nut 34 having three slots therein is shown in Figure 13.

Instead of forming a circumferential groove purely circular in form as shown in Figures 12 and 14, a groove tapering only in the plane perpendicular to the axis of the nut may 5 be formed. Such tapered circumferential groove is shown in Figure 13. It is to be noted that the floor 35 of the circumferential groove is always in a plane perpendicular to the axis of the nut and does not taper upward. 10 The elements of the wall 36 of the circumferential grooves are parallel to the axis of the nut. The elements of the walls in the plane at right angles to the axis of the nut such as 15 40 and all parallel planes beneath it taper as shown. To produce such circumferential groove the contour of the shoulder 20 must be modified to the shape of the taper required as shown at 41 in Figures 10 and 11.

The above changes are only some of the 20 many which may be made without departing from the spirit of my invention. All such changes I view as falling within my invention and disclosure.

Having described my invention what I 25 claim as new and useful is:—

As an article of manufacture a forming die, for use in combination with a punch and crowner for producing a nut having a bore, a circumferential groove and one or more 30 slots leading into the said groove, consisting of a body member having an aperture formed therein to produce the nut cross section desired, one or more cutter receiving slots formed in the said die, and a cutter for cutting 35 the said nut slots detachably mounted in each of the said cutter receiving slots and positioned so that its cutting edge projects into the said aperture.

In testimony whereof I hereby affix my 40 signature.

CHARLES HOPKINS.
